UNITED STATES PATENT OFFICE.

NATHAN W. CONDICT, JR., OF JERSEY CITY, NEW JERSEY.

BALANCED SLIDE-VALVE.

SPECIFICATION forming part of Letters Patent No. 275,356, dated April 10, 1883.

Application filed January 9, 1882. Renewed September 11, 1882. (No model.)

To all whom it may concern:

Be it known that I, NATHAN W. CONDICT, Jr., a citizen of the United States, residing in Jersey City, New Jersey, have invented certain Improvements in Balanced Slide-Valves, 5 of which the following is a specification.

My invention relates to a device for relieving the slide-valves of steam-engines from undue pressure of steam; and my invention consists mainly in combining a slide-valve with certain balanced bars secured within the valve-chest for the above purpose.

In the accompanying drawings, Figure 1 is a transverse section of a valve-chest with my 15 improved balanced valve; Fig. 2, a longitudinal section of the valve-chest and side view of the valve; Fig. 3, a perspective view of the valve drawn to a reduced scale; and Fig. 4, a view of a modification, also drawn to a reduced scale.

In Figs. 1 and 2, A represents the valve-face of a steam-cylinder; a a', the usual steam-ports, and b the exhaust-port.

B is the slide-valve, which, with the exception of the wings d d, referred to hereinafter, 25 may be similar to those of ordinary construction, the valve having in the under side the usual recess, forming an exhaust-passage, and in the top a recess for the valve-spindle, which 30 is secured to the valve in any well-known manner, and passes through a stuffing-box in the valve-chest D.

Two balance bars or plates, G G, bear each 35 on two supports, H H, secured, in the present instance, to the valve-face A. Each balance-bar is confined to the tops of the supports by a spring, J, on which, near the ends, bear nuts m m, adapted to bolts I, projecting upward from the supports H. By turning these 40 nuts the bar may be forced down onto the supports with more or less pressure through the medium of the spring. A nice adjustment of the balance-bars will be required, so that while they are always in rigid contact with the supports they shall always bear lightly on the wings d d, and so that, while no undue friction is created by the sliding of the wings of the valve in contact with the balance-bars, the steam admitted to the chest cannot get between the bars and the wings of the valve. 45

The only portion of the top of the valve exposed to the pressure of steam is that between the bars G G, and this pressure is in part counteracted by that against the under side of the wings d d; but the area of these wings 55 should be so regulated that there shall be a slight excess of pressure on the top of the valve, so that it will always keep its seat. It is not essential that the balance-bars should be secured to the valve-face A of the steam-60 cylinder.

In Fig. 4 two vertically-adjustable angle-bars are secured to the sides of the steam-chest, and are arranged to cover so much of an ordinary slide-valve that the pressure of 65 steam on the latter will be greatly diminished.

The springs J for keeping the balance-bars down on their bearings are not essential; but I prefer them, because a yielding pressure applied to the bar is, in my opinion, superior to 70 a rigid pressure.

Instead of the rigid bearings H H for the balance-bars, these supports may consist of springs capable of yielding to the pressure exerted by manipulating the nuts m when vertical adjustment is required, but too strong to yield to the pressure of steam, for it is essential to my invention that the bars should be substantially fixed within the steam-chest. 75

The balance-bars may, if desired, be united 80 or made in one piece; but I prefer separate bars.

I claim as my invention—

1. The combination of a slide-valve with balance-bars secured within the valve-chest 85 and adapted to the back of the valve, substantially in the manner described.

2. The combination of a slide-valve having wings d d, with balance-bars G G, secured within the valve-chest and adapted to the 90 valve and its wings, substantially in the manner described.

In testimony whereof I have signed my name to this specification in the presence of two subscribing witnesses.

N. W. CONDICT, JR.
